UNITED STATES PATENT OFFICE.

ETTORE E. BAYARDI, OF CHICAGO, ILLINOIS, ASSIGNOR TO BAYARDI BROS. INC., OF CHICAGO, ILLINOIS, A CORPORATION OF ILLINOIS.

DESIGN FOR A FINGER RING.

Application filed August 8, 1925. Serial No. 14,356. Term of patent 14 years.

To all whom it may concern:

Be it known that I, ETTORE E. BAYARDI, a citizen of the United States, residing at Chicago, in the county of Cook and State of Illinois, have invented a new, original, and ornamental Design for a Finger Ring, of which the following is a specification, reference being had to the accompanying drawing, forming part thereof.

Figure 1 is a side elevation of a finger ring embodying my design.

Fig. 2 is a face or edge view thereof, and

Fig. 3 is a section on the line 3—3 of Fig. 1.

My design consists of a ring with plane sides and with settings which are approximately triangular or substantially trapezoidal in shape disposed alternately, that is,

with their apices in alternate arrangement, as best illustrated in Fig. 2.

And the design also consists in having the openings in the inner wall of the ring also of triangular or substantially trapezoidal shape and in alternate arrangement, as best illustrated in Fig. 3.

The outermost faces of the settings all lie within the plane of the outermost circumference of the ring blank as clearly illustrated in Fig. 1, and the triangular or substantially trapezoidal outermost faces of the settings are flat or plane, as shown.

I claim:

The ornamental design for a finger ring, as shown and described.

ETTORE E. BAYARDI.
